UNITED STATES PATENT OFFICE.

ELIZABETH T. HINCKS, OF ANDOVER, MASSACHUSETTS.

DOLL.

No. 853,639.

Specification of Letters Patent.

Patented May 14, 1907.

Application filed February 28, 1907. Serial No. 359,791.

To all whom it may concern:

Be it known that I, ELIZABETH T. HINCKS, of Andover, county of Essex, State of Massachusetts, have invented an Improvement in 5 Dolls, of which the following description, in connection with the accompanying drawings, is a specification, like characters on the drawings representing like parts.

This invention relates to dolls or similar 10 playthings for children, and has for its object to provide a doll with means whereby it may be heated and kept warm for a long period of time and the child thereby enabled to enjoy the luxury of handling a warm doll instead of 15 handling a cold doll with the attending liability of taking cold.

The doll embodying my invention is constructed and arranged to be heated throughout its body and head, either or both, and 20 when thus heated the child can take the doll to bed with her and feel the warmth of the doll and enjoy it, or the body and head of the doll, either or both, may be filled with cold water or water (hot or cold) and air, or air, or 25 it may be filled with cracked ice, or ice water and used as an ice bag.

Figure 1 shows in front elevation and partial vertical section a doll embodying this invention, the flexible water-proof bag contained within it being filled with hot water, thereby filling out the previously collapsed body and head. Fig. 2 is a vertical section of the doll shown in Fig. 1. Fig. 3 is a vertical section of the doll shown in Fig. 1, in 35 collapsed condition, previous to filling the flexible water-proof bag with hot water or other material. Fig. 4 is a detail showing the opening through which the neck of the bag may be projected, for the purpose of filling or emptying the bag.

The doll comprises a body *a*, head *b*, arms *c*, *c*, and legs *d*, *d*. The body and head are herein shown as made hollow and in open communication, yet so far as my invention is concerned the body or head only need be made hollow.

The doll may be made of a piece or pieces of cloth, or knit goods or other form of textile material, arranged to form a flexible hollow body and head. The arms and legs may be made of the same piece or pieces of cloth if desired, or they may be otherwise constructed and stuffed with any suitable material. The material composing the doll may 55 be printed, painted, lithographed or other-

wise marked to represent the face, hands, etc.

I do not desire to limit my invention to the particular construction of the doll, so long as it is adapted to be used to carry out the ideas 60 embodying my invention.

The flexible hollow body and head, either or both, contains within it a flexible water-proof bag *e*, adapted to contain hot or cold water, or air, either or both, although it may 65 contain cracked ice, or ice water, or other material. This bag is or may be composed of rubber or essentially of rubber, and is adapted, when filled, to conform to the shape of the body and head, either or both of which 70 contain it.

The flexible water-proof bag has at any desirable point an open neck or orifice *e'*, which is adapted to be closed by a stopper *e''*, and preferably has a funnel at the neck to 75 facilitate filling the bag with water. As herein shown the bag has a neck which extends through an opening in the body of the doll and projects into one leg thereof, and said leg is slotted see Fig. 4 to provide an 80 opening by which access may be had to the neck for the purpose of filling the bag or for emptying it, or for the purpose of withdrawing or introducing the bag. This manner of providing an inlet to the water-proof bag is simple and convenient, but it is obvious that inlets of other forms may be employed. My invention, however, comprehends the employment of a stopper adapted to provide for filling the bag partially or wholly with water, 85 or air.

The flexible water-proof bag, when empty, collapses, and the body and head of the doll likewise collapse, as shown in Fig. 3, but when the bag is filled said body and head are 95 filled or expanded and caused to assume the shape which it is intended they shall assume.

It is obvious that the body may be made in different shapes, the shape here shown being merely selected for the purpose of illustrating my invention.

Having thus described my invention, what I claim as new and desire to secure by Letters Patent is:—

1. A doll consisting of a hollow body having 105 a head, and arms and legs, a flexible water-proof bag contained in said hollow body having an open neck and a stopper for the opening thereof, substantially as described.

2. A doll consisting of a hollow body and a 110

hollow head in open communication, and having arms and legs, a flexible water-proof bag contained in said hollow body and head having an open neck and a stopper for the opening thereof, substantially as described.

3. A doll consisting of a hollow body having a head, and arms and legs, a flexible water-proof bag contained in said hollow body having a flexible neck extended through an opening in said body and provided with an orifice and a stopper for said orifice, substantially as described.

4. A doll consisting of a flexible hollow body having a head, and arms and legs, and a flexible water-proof bag contained in said hollow body having an orifice provided with a stopper, substantially as described.

5. A doll consisting of a flexible hollow body having a flexible hollow head and having arms and legs, and a flexible water-proof bag contained in said hollow body having an open neck provided with a stopper, substantially as described.

6. A doll consisting of a hollow body having an opening and having a head, and arms and legs, a flexible water-proof bag contained in said hollow body adapted to be withdrawn through said opening, which is provided with an open neck having a stopper, substantially as described.

7. A doll consisting of a hollow body having an opening and having a head, and arms and legs, and a flexible water-proof bag contained in said hollow body adapted to be withdrawn through said opening and having a neck which extends through said opening which is provided with an orifice and a stopper therefor, substantially as described.

In testimony whereof, I have signed my name to this specification, in the presence of two subscribing witnesses.

ELIZABETH T. HINCKS.
